UNITED STATES PATENT OFFICE.

HAZEL KELLEY, OF SAN JOSE, CALIFORNIA.

DESIGN FOR A DOLL.

58,388.

Specification for Design. Patented July 12, 1921.

Application filed December 24, 1920. Serial No. 433,079. Term of patent 14 years.

To all whom it may concern:

Be it known that I, HAZEL KELLEY, a citizen of the United States, and a resident of San Jose, in the county of Santa Clara and State of California, have invented a new, original, and ornamental Design for Dolls, of which the following is a specification, reference being had to the accompanying drawing, forming part thereof.

I claim:

The ornamental design for a doll, as shown.

HAZEL KELLEY.
